UNITED STATES PATENT OFFICE

2,543,619

PAPER DISH AND HOLDER THEREFOR

Walter E. Amberg, Beverly Shores, Ind., assignor,
by mesne assignments, to Lily-Tulip Cup Corporation, New York, N. Y., a corporation of Delaware

Application September 7, 1946, Serial No. 695,495

7 Claims. (Cl. 65—61)

1

This invention relates to paper dishes and holders therefor.

An object of this invention is to provide an improved conical paper dish which may be more readily received and positively secured in a holder for lining the same.

Another object of this invention is to provide an improved holder for conical paper dishes which will more readily receive and positively secure the paper dishes therein.

A further object of this invention is to provide an improved holder for conical paper dishes which may be readily stacked.

In carrying out the objects of the invention, the paper dish is preferably formed from a circular paper blank and provided with diametrically opposed folded sectoral flaps or plaits. The holder for the paper dishes preferably includes a base and a conical bowl which is provided with diametrically opposed circumferentially extending fingers for receiving the diametrically opposed folded flaps or plaits and which is provided with an annular groove conforming to the dimension of the bottom of the base to facilitate stacking.

The paper dish is received in the conical bowl and by rotating the conical bowl relative to the paper dish the folded flaps or plaits are received under the fingers. Because the paper dish is provided with diametrically opposed folded flaps or plaits the maximum relative rotation required to receive the folded flaps or plaits under the fingers is limited to substantially 180 degrees of rotation thereby facilitating greatly the reception of the dish in the holder. Since the holder is provided with opposed fingers for receiving the opposed folded flaps or plaits, the paper dish is positively secured in the holder at opposed points thereby greatly reducing the tendency of the paper dish from working free from the holder. The annular groove in the holder permits stacking of the holders one on top of the other thereby avoiding the necessity of pyramid type stacking and saving stacking space.

Other objects and advantages will become apparent to those skilled in the art upon reference to the accompanying specification, claims, and drawing, in which—

Fig. 1 is a perspective view of the holder of this invention;

Fig. 2 is a side elevational view of the holder shown in position for receiving a paper dish from an inverted stack of dishes;

Fig. 3 is a perspective view of the paper dish;

Fig. 4 is a partial plan view of the paper blank for forming the paper dish;

Fig. 5 is a vertical sectional view through the holder;

Fig. 6 is a partial sectional view through the holder and finger taken along the line 6—6 of Fig. 5;

Fig. 7 is a view illustrating the stacking of a plurality of holders.

2

The paper dish of this invention is generally designated at 10 while the holder therefor is generally designated at 11. The holder 11 is adapted to receive the paper dish 10 and may operate to 5 pick up a dish from a plurality of dishes contained in an inverted stack of dishes 12, as illustrated in Fig. 2.

The paper dish 10 is formed from a circular paper blank 13, as shown in Fig. 4. The paper blank 13 is provided with opposed creases 14 and 15 extending diametrically through the center of the blank for forming diametrically opposed folded sectoral flaps or plaits 16, as illustrated in Fig. 3. The creases 14 appear on the outside of 15 the dish and the creases 15 appear on the inside thereof. When the folded flaps or plaits 16 are formed along the creases 14 and 15, the paper dish assumes a conical shape. The flaps or plaits 16 face in the same rotative direction.

10 The holder 11 includes a base 20 and a conical bowl 21. The bottom of the base 20 terminates in an annular foot 22 and the upper portion of the base 20 terminates in a screw-threaded ring 23. The base 20 may be provided with reinforcing ribs 24.

15 The bowl 21 is provided with a screw threaded extension 26 to telescopically and screw-threadedly receive the ring 23 whereby the bowl 21 is carried by the base 20. The bowl 21 may be provided with recesses 27 to accommodate a suitable tool to assist in the assembly of the bowl on the base. The bowl 21 is provided with a pair of oppositely disposed openings 28 and circumferentially extending spring fingers 29 secured to the 20 bowl 21 by rivets 30 overlie the openings 28 and face in the same rotative direction.

25 The conical paper dish 13 is received in the conical bowl 21 and when the dish and bowl are relatively rotated, the opposed folded flaps or 30 plaits 16 are received under the opposed fingers 29. The flaps are warped by the action of the fingers 29 and are tightly secured between the fingers 29 and the edges of the openings 28. In 35 this way the flaps 16 are securely held in place under the fingers 29. Because the paper dish is provided with diametrically opposed flaps, the maximum relative rotation required to receive the folded flaps under the fingers is limited to substantially 180 degrees of rotation, thereby

40 facilitating greatly the reception of the dish in the holder. Since the holder is provided with opposed fingers for receiving the opposed flaps, the paper dish is positively secured in the holder at opposed points, thereby greatly reducing the 45 tendency of the paper dish from working free from the holder.

The bowl 21 is provided with an annular groove 32 which conforms in dimension to the annular foot 22 of the base 20 and preferably the 50 outside of the bowl 21 is enlarged as at 33 for the purpose of accommodating the groove 32. The groove 32 is adapted to receive the foot 22 of the 55

base of another holder so that a plurality of holders may be stacked one on top of the other without any danger of tipping. In this way considerable space is saved in the stacking of holders for with this arrangement it is no longer necessary to stack holders in pyramid fashion.

While for purposes of illustration one form of this invention has been disclosed, other forms thereof may become apparent to those skilled in the art upon reference to this disclosure and, therefore, this invention is to be limited only by the scope of the appended claims and prior art.

I claim as my invention:

1. A holder for a conical paper dish provided with diametrically opposed folded flaps comprising, a base adapted to receive and support a conical paper dish therein, a conical bowl carried by the base, diametrically opposed circumferentially extending fingers in the side wall of the conical bowl for receiving the diametrically opposed folded flaps of the conical paper dish and an annular groove in the side wall of the conical bowl conforming to the dimension of the bottom of the base for receiving the bottom of the base of another holder to facilitate stacking of a plurality of holders.

2. In combination, a conical paper sundae dish formed from a substantially circular paper blank and provided with diametrically opposed folded sectoral flaps extending from the apex of the conical paper dish to the edge thereof and having side creases extending diametrically through said apex, and a holder for said conical paper sundae dish comprising a base, a conical bowl carried by the base for receiving and supporting the conical paper sundae dish therein and diametrically opposed circumferentially extending fingers in the side wall of the conical bowl and facing in the same rotative direction for receiving and gripping the diametrically opposed folded sectoral flaps of the conical paper sundae dish upon limited relative rotation of the conical paper sundae dish and the holder automatically to grip and secure the conical paper sundae dish at diametrically opposed points in the conical bowl of the holder.

3. In combination, a conical paper sundae dish formed from a substantially circular paper blank and provided with diametrically opposed folded sectoral flaps extending from the apex of the conical paper dish to the edge thereof and having side creases extending diametrically through said apex, and a holder for said conical paper sundae dish comprising a base, a conical bowl carried by the base for receiving and supporting the conical paper sundae dish therein and having diametrically opposed openings in the side wall thereof and circumferentially extending fingers in the side wall of the conical bowl overlying the openings and facing in the same rotative direction for receiving and gripping between the fingers and the edges of the openings the diametrically opposed folded sectoral flaps of the conical paper sundae dish upon limited relative rotation of the conical paper sundae dish and the holder automatically to grip and secure the conical paper sundae dish at diametrically opposed points in the conical bowl of the holder.

4. A conical paper sundae dish for lining a conical holder and formed from a substantially circular paper blank and provided with only two diametrically opposed folded sectoral plaits extending from the apex of the conical paper sundae dish to the edge thereof and facing in the

same rotative direction and with the side creases of the plaits extending diametrically through said apex.

5. A holder for a conical paper sundae dish provided with diametrically opposed folded flaps comprising a base, a conical bowl carried by the base adapted to receive and support the conical paper sundae dish therein, and diametrically opposed circumferentially extending fingers in the 10 side wall of the conical bowl and facing in the same rotative direction adapted to receive and grip the diametrically opposed folded flaps of the conical paper sundae dish upon limited relative rotation of the holder and the conical paper sundae dish for automatically gripping and securing the conical paper sundae dish at diametrically opposed points in the conical bowl of the holder.

6. A holder for a conical paper sundae dish 20 provided with diametrically opposed folded flaps comprising a base, a conical bowl carried by the base adapted to receive and support the conical paper sundae dish therein and having diametrically opposed openings in the side wall thereof, and circumferentially extending fingers in the 25 side wall of the conical bowl overlying the openings and facing in the same rotative direction adapted to receive and grip between the fingers and the edges of the openings the diametrically 30 opposed flaps of the conical paper sundae dish upon limited relative rotation of the holder and the conical paper sundae dish for automatically gripping and securing the conical paper sundae dish at diametrically opposed points in the conical bowl of the holder.

7. A holder for a conical paper dish comprising, a base, a bowl carried by the base and comprising a conical side wall adapted to receive and support a conical paper dish therein, and an annular groove in the conical side wall of the bowl 40 between the top and bottom thereof conforming to the dimension of the bottom of the base for receiving the bottom of the base of another holder to facilitate stacking of a plurality of holders.

WALTER E. AMBERG.
